UNITED STATES PATENT OFFICE.

MARK W. DEWEY, OF SYRACUSE, NEW YORK, ASSIGNOR OF TWO-THIRDS
TO EMIL LAASS AND CHARLES H. DUELL, OF SAME PLACE.

ELECTRIC-HEATING APPARATUS FOR RAILWAY SYSTEMS.

SPECIFICATION forming part of Letters Patent No. 401,482, dated April 16, 1889.

Application filed January 25, 1889. Serial No. 297,499. (No model.)

To all whom it may concern.:

Be it known that I, MARK W. DEWEY, of Syracuse, in the county of Onondaga, in the State of New York, have invented new and 5 useful Improvements in Electric-Heating Apparatus, of which the following, taken in connection with the accompanying drawings, is a full, clear, and exact description.

My invention relates to heating electrically-propelled vehicles, but more especially street-cars, receiving the current by means of movable contacts from stationary supply conductors along the roadway; and it consists in placing suitable electric-heating devices in a 10 conductor upon a car, either within, for the purpose of warming the interior, or outside, and supported in proximity to the supply-conductors, which may be wires overhead within a conduit or the tracks of the car, for the purpose of thawing the ice and snow that often 15 form and collect upon them, obstructing to an extent the free passage of the current from the supply-conductors to the motor.

The object of this invention is to keep the 20 supply-conductors clear, so that the motor will be supplied with an increased, constant, and uniform current, and the supply-conductors freed from snow and ice, relieving them oftentimes of considerable weight and strain, which 25 tend to sag and break them down, and, by the increased current-supply, enabling electric-heating devices within the car to be supplied with the necessary amount of current for warming the interior without greatly increasing 30 the current in the supply-conductors.

The advantages derived by electrically heating cars are apparent. The heating devices may be placed under the seats, thereby allowing more seat-room. They are less dangerous than stoves, and, not requiring coal 35 and the removal of ashes, are cleaner and less troublesome and less expensive.

In the accompanying drawings, Figure 1 represents an electric street-car receiving the current by a movable contact on a stationary overhead conductor and a movable contact on the track which forms the return-conductor. Electric-heating devices are shown in proximity to the contacts for heating the same 40 and beneath the car-seat, where the side of the car is broken away, for warming the in-

terior of the car. Fig. 2 represents means for supplying the heating devices with a heating-current of low electro-motive force, but great quantity. Fig. 3 shows the heating devices 55 in series, with the motor and shunts for cutting them out when desired. Fig. 4 is a view of a trolley, partly in section, with heating device and cut-out. Fig. 5 illustrates a modification of the attachment of the heating device to the trolley. Fig. 6 is a view in perspective of a preferred form of heating device to be placed in proximity to the contacts. Fig. 7 shows heating devices supported on a car in contact with the conductors, but disconnected from the electrical contacts of the conductor leading to the motor on the car. Fig. 8 shows the heating devices supported in proximity to the conductors without contact therewith. Fig. 9 is a cross-section of a conduit and an end view of a car with a heating device suspended from the latter and traveling within said conduit in proximity to the conductors; and Fig. 10 is a plan view of the running-gear of a car, provided with means 70 for throwing the same out of gear with the motor.

Referring specifically to the drawings, A in Fig. 1 represents the car; M, the motor for propelling the car; C, the overhead supply conductor; C', the track or return conductor; T, the trolley; c, the wheel or movable contact on the trolley; T', the support for the movable contact on the track; c', the movable contact on the track; h h', the heating devices on said contacts, and H the heating device beneath the seat of the car.

In Fig. 2, M represents the motor on the car; B, the conductor leading through said motor; c and c', the terminals of said conductor, 80 which terminals also represent the movable contacts. P is a continuity-preserving-current-pole-changer in the conductor, which is connected rigidly to the shaft of said motor and rotated thereby. The current supplied 85 to the motor to run the same is in this case continuous and of high tension, and in order to obtain a heating-current of great quantity, but low electro-motive force, it is necessary to alternate the current in a portion of the conductor B' which is connected with a transformer, D, and form the secondary circuit S

of the transformer of large wire. The secondary circuit contains the heating-conductors h h' and H in series. s s indicate direct low-resistance shunt-paths for the current around the heating devices, that may be closed by suitable switches or circuit-closers, s' , when it is desired to cut out said heating devices H , h , or h' . The switch s' for the shunt s of H may also be moved to break the secondary circuit S completely when desired. This may be accomplished by moving the switch to point p . It will be obvious that when the current for propelling the car is of an alternating character the pole-changer may be dispensed with; but most electric railways employ continuous or direct currents, and in order to transform said current, after supplying the motor for propelling the car, into an increased heating-current the former current should be alternated in a portion of the conductor including the primary coil of a suitable transformer. By this plan the motor is supplied with the necessary continuous current to propel the car, and only that portion of the conductor containing the coil of the transformer has alternations therein, and by operating the pole-changer by the motor propelling the car an extra motor for this purpose is not necessary. The motor may be operated for supplying the heating device with a heating-current, even when the car is at rest, by uncoupling the motor M from the car in any suitable and well-known manner, Fig. 10 of the drawings illustrating one of the means for uncoupling the motor, and consists of a friction-clutch member, E , sliding on the driving-axle and engaging a clutch member fixed to the side of the driving gear-wheel G , mounted loosely on the axle, the clutch member E being connected with the axle by spline and groove in the usual manner. A bell-crank lever, F , is pivoted to the car-frame and engages at one end with the sliding clutch member, and has the opposite end connected with a manipulative lever, F' , pivoted to the end of the car in a convenient position to be manipulated by the person in charge of the car.

In Fig. 3, M represents the car-motor, as in Fig. 2; c and c' , the movable contacts; h , h' , and H , the heating devices, and s s the shunts. When the shunts are open and the circuit including the heating devices, is closed, said devices are heated by the passage of the current through them, and when it is desired to cut out one or more of said heating devices the shunt-paths for the current are closed. All the devices may be cut out at once by breaking the supply-circuit, as by moving the switch s' to point p . (Shown in Fig. 2.)

Fig. 4 shows a trolley, T , partly in section, to show the arrangement of the heating device h for use in connection with the circuit passing through the motor, as represented in Fig. 2. c being the wheel or movable contact that runs on the stationary supply-conductor C .

In the position shown in the figure, as the current enters the wheel it passes through its pivots to the support d , then to the heating device h , and through the same to the trolley T . The divided core i is separated at o , and the shield or case a is insulated from d at n , so that the current must pass through the heating-coil. This heats the support d and wheel c , so as to thaw ice or snow that may have collected on the stationary conductor C . When the conductor is freed from ice, the current may be shunted or passed through an other path to the motor, so as not to heat the 80 device. This is done by closing the divided parts of the core i , which forms the shunt. In order to permit of the aforesaid opening and closing of the shunt, I provide the base of the shield a with a screw-threaded socket, b , and the trolley-rod T with a corresponding screw-threaded portion, by which it is connected to the socket b . A jam-nut, t , on the rod T serves to hold the parts firmly in either position.

Fig. 5 shows a heating-coil on a trolley connected with a secondary circuit, as at S in Fig. 2. s' is the switch for shunting the heating-coil, and is shown open. By turning said switch on its pivot so as to bring its ends in contact with the points a' and a'' the current is allowed to freely pass through said switch s' without passing through the heating-coil. The trolley beneath the car and bearing on the track is of substantially the same construction as that of the trolley above the car, hereinbefore described, and may be suspended in any suitable manner from the car.

Fig. 6 is a preferred form of heating device, h , specially adapted for a movable contact, and consists of a thin strip of metal, which may be copper, iron, or other suitable material, formed spirally or coiled; so that a core of heat-conducting substance may be inserted.

In Fig. 7, h and h' designate heating devices supported on a car, A , in contact with the conductors C and C' . In this case, however, each of said heating devices has two contacts running on the conductor for communicating to said conductor an increased heating effect, and both heating devices are placed at a distance from the contacts c and c' , so that said contacts will not become heated.

In Fig. 8 the heating devices h and h' are supported on a car, A , in close proximity to the conductors C and C' , but not in contact therewith, and are extended parallel with a considerable portion of said conductor. By this arrangement I am enabled to supply the conductors with a great heating effect without friction and wear upon the conductors. In Fig. 9 the heating device h is suspended from a car and within a conduit, N , and close to the conductors C and C' therein.

The shield or case a may be made of heat-non-conducting material, if desired.

Having described my invention, what I claim as new, and desire to secure by Letters Patent, is—

1. The combination, with an electrically-propelled vehicle receiving its current from stationary supply-conductors along the path of the vehicle, and a conductor on the vehicle having its terminals connected with movable contacts on said stationary conductors, of an electric-heating device carried on the vehicle in contact with or in proximity to one of said stationary conductors, for the purpose set forth.
2. The combination, with an electrically-propelled vehicle receiving a continuous current from stationary supply-conductors along the path of the vehicle and a conductor on the vehicle having its terminals connected with movable contacts on said stationary conductors, of a continuity-preserving-current pole-changer operated by the electric motor propelling the vehicle and in circuit with said motor, a portion of the vehicle-conductor having its current therein alternated by the pole-changer, a transformer having its primary coil in circuit with the portion of the conductor wherein the current is alternated and its secondary coil in circuit with a heating device, and a device for cutting out or in the said heating device, as set forth.
3. In combination with an electrically-propelled vehicle receiving a continuous current from stationary supply-conductors along the path of the vehicle and a conductor on the vehicle having its terminals connected with movable contacts on said stationary conductor, two or more suitable electric-heating devices in series and a shunt containing a making and breaking device around each of said heating devices, as set forth.
4. In combination with an electrically-propelled vehicle, the supply-conductor on the vehicle, an electric-heating device connected with said supply-conductor, and a direct low-resistance shunt-path for the current around said heating device containing a circuit maker and breaker.
5. The combination, with an electrically-propelled vehicle and the supply-conductors and motor thereon, of a continuity-preserving-current pole-changer operated by the electric motor propelling the vehicle and in circuit with said motor, a portion of the vehicle-conductor having its current therein alternated by the pole-changer, a transformer having its primary coil in circuit with the portion of the conductor wherein the current is alternated and its secondary coil in circuit with a heating device, means for cutting out the said heating device, and suitable means also on the vehicle for throwing the motor out of gear with the driving-axle of the vehicle, so that the motor may operate the pole-changer when the vehicle is at rest, as set forth.
6. The combination of a movable vehicle, a stationary electric conductor along the path of said vehicle, and a suitable heating device supported on the vehicle in contact with or in close proximity to said stationary conductor.
7. The combination, with a movable contact or trolley of an electrically-propelled vehicle, of an electric-heating device on said movable contact or trolley, for the purpose of heating the same.
8. The combination, with a movable contact or trolley of an electrically-propelled vehicle, of a suitable heating device carried by said trolley in contact with or in proximity to a stationary supply-conductor, as set forth.
9. An electric-heating device consisting of a thin strip of metal coiled or formed spirally, a divided core of metal within the said heating device, means for connecting and disconnecting the parts of the core to shunt the heating device, and a suitable shield or case enveloping said device, as set forth.
10. The combination, with a vehicle, stationary electric supply-conductors along the path of said vehicle, a source of continuous current connected thereto, and a conductor on the vehicle having its terminals connected with movable contacts on said stationary supply-conductors, of a continuity-preserving-current pole-changer and an electric motor for operating the same both upon the vehicle and in circuit with the vehicle-conductor, a portion of the vehicle-conductor having its current therein alternated by the pole-changer, a transformer having its primary coil in circuit with a portion of the conductor wherein the current is alternated and its secondary coil in circuit with a heating device, and means for cutting out the said heating device, as set forth.
11. The combination, with an electrically-propelled vehicle receiving a continuous current from stationary supply-conductors along the path of the vehicle and a conductor on the vehicle having its terminals connected with movable contacts on said stationary conductors, of a continuity-preserving-current pole-changer operated by the electric motor propelling the vehicle and in circuit with said motor, a portion of the vehicle-conductor having its current therein alternated by the pole-changer, a transformer having its primary coil in circuit with the portion of the conductor wherein the current is alternated and its secondary coil in circuit with a heating device, means for cutting out the said heating device, and suitable means also on the vehicle for throwing the motor out of gear with the driving-axle of the vehicle, so that the motor may operate the pole-changer when the vehicle is at rest, as set forth.

In testimony whereof I have hereunto signed my name, in the presence of two witnesses, at Syracuse, in the county of Onondaga, in the State of New York, this 21st day of January, 1889.
